PUMP

Cyrus C. Jetter, Grand Rapids, Mich.

Application September 13, 1943, Serial No. 502,082

8 Claims. (Cl. 103—195)

This invention relates to improvements in pumps.

The main objects of this invention are:

First, to provide a packing for the pump rods of oil well and like pumps which is capable of withstanding the severe working conditions to which such pumps are subjected in use, at the same time allow a freer movement of the pump rod packing plunger or the packed portion of the pump rod whereby the wear is reduced to a minimum.

Second, to provide a resilient supporting connection between the pump rod packing cylinder and the casing which permits the adjustment of the reciprocating parts to each other and thereby minimizes friction and wear.

Third, to provide a structure in which a plurality of packing rings are spaced throughout the length of the packing plunger thereby providing a long bearing with sufficient clearance between the plunger and the cylinder to minimize friction and at the same time provide an efficient seal.

Fourth, to provide a structure having these advantages which may be adapted to standard or widely used types of pumps.

Objects relating to details and economies of the invention will appear from the description to follow. The invention is defined in the claims.

A preferred embodiment of the invention is illustrated in the accompanying drawing, in which:

Fig. 1 is a fragmentary side elevation partially in longitudinal section of a structure embodying my invention as applied to an oil well pump.

Fig. 2 is an enlarged fragmentary view mainly in longitudinal section illustrating the details of the mounting of the packing cylinder in its relation to the pump casing.

Fig. 3 is a fragmentary view partially in longitudinal section of a modified form or embodiment of my invention.

In the embodiment illustrated, 1 represents the tubular pump casing or the upper end of the pipe of a well and 2 the plunger rod. 3 is a T-fitting threaded on the end of the casing and has an oil outlet pipe 4 connected thereto. Threaded into the outer end of this coupling is an adapter 5 having an internal bore 6 and externally threaded at 7 to receive the clamping sleeve or cap 8. The sleeve 8 has an inturned flange 9 at its upper end. The pump rod packing cylinder projects into the casing 1 a substantial distance and also projects from the casing. The pump rod packing cylinder 11 reciprocates within this cylinder 10.

The cylinder 10 is provided with an annular flange 12, preferably formed separately therefrom but fixedly secured thereto as by welding as indicated at 13. This supporting member is

disposed between the rubber or other resilient supporting elements 14, the inner of which is seated on the end of the adapter 5 and the outer of which is between the flange 9 and the supporting flange 12 on the cylinder.

The diameter of the cylinder relative to the internal diameter of the casing 1, the adapter 5, and the flange 9 of the clamping collar is such as to permit a substantial tilting movement of the cylinder which is permitted by its resilient supporting elements. These supporting members also constitute packing members.

The pump rod packing plunger is provided with a plurality of vertically spaced packing ring grooves 15 which are preferably arranged in vertically spaced groups as illustrated. The split packing or plunger rings 16 are preferably of the resilient metallic type and they are arranged in the grooves. The packing ring grooves are of sufficient depth to allow free radial movement of the packing rings therein and they also have sufficient tolerance in their axial width to permit this free movement. This provides an effective packing while permitting clearance between the packing plunger and the cylinder to allow very free reciprocating movement of the plunger.

The packing cylinder is of such length as to allow a long stroke and also to house the substantially spaced packing rings.

In the embodiment of my invention shown in Fig. 3, the clamping sleeve 17 is threaded directly upon the take-off coupling 3. In this case, an annular thrust member 18 is seated on the end of the take-off coupling 3 to support the inner of the resilient support members 14.

In structures embodying my invention, it is not necessary to replace the packings frequently as is necessary in the widely used type of oil pumps. I attribute the wear on the packing in these pumps quite largely to the swaying of the pump rod during the reciprocating movement thereof. This results in wearing the packing out of round and soon necessitates the re-packing or results in the leaking of oil which is not only wasteful but constitutes serious fire hazard. It has been demonstrated by use that my invention cuts this replacement to a minimum. The swaying or tilting of the pump rod does not produce undue wear on the packing and, further, the packing rings are so arranged throughout the length of the packing rod that a long bearing is provided and this also minimizes wear on the cylinder wall or on the plunger.

The time element is also an important factor as it is not necessary to stop the pumping operation when the packings are being renewed or replaced, and further than that, the packing rings are very long lived and while they provide an effective seal they are sufficiently lubricated to avoid excessive wear.

I have illustrated and described my improvements in highly practical embodiments thereof. I have not attempted to illustrate or describe other adaptations or embodiments as it is believed that this disclosure will enable those skilled in the art to embody or adapt my invention as may be desired.

Having thus described my invention, what I claim as new and desire to secure by Letters Patent, is:

1. In a pump, the combination of a tubular casing provided with a take-off T-coupling, an adapter threaded into the upper arm of said coupling, a pump rod packing cylinder extending into said casing and provided with an annular supporting flange, annular resilient supporting elements arranged one above and the other below said flange, the lower element being seated on the end of said adapter, a clamping sleeve threaded upon said adapter and having an inturned flange at its outer end engaging the resilient support element, the diameter of said packing cylinder being substantially less than the internal diameters of the casing, the adapter, and of the flange of said clamping sleeve, whereby substantial tilting movement of said cylinder on its said resilient supporting elements is permitted, a pump rod provided with a packing plunger reciprocating within said packing cylinder and having vertically spaced groups of packing ring grooves, and split resilient metallic packing rings arranged in said packing ring grooves.

2. In a pump, the combination of a tubular casing provided with a take-off T-coupling, an adapter threaded into the upper arm of said coupling, a pump rod packing cylinder extending into said casing and provided with an annular supporting flange, annular resilient supporting elements arranged one above and the other below said flange, the lower element being seated on the end of said adapter, a clamping sleeve threaded upon said adapter and having an inturned flange at its outer end engaging the resilient support element, the diameter of said packing cylinder being substantially less than the internal diameters of the casing, the adapter, and of the flange of said clamping sleeve, whereby substantial tilting movement of said cylinder on its said resilient supporting elements is permitted, and a pump rod provided with a packing plunger reciprocating within said packing cylinder.

3. In a pump, the combination of a tubular casing provided with a take-off T-coupling, an adapter threaded into the upper arm of said coupling, a pump rod, a pump rod packing cylinder extending into said casing and provided with an annular supporting flange, annular resilient supporting elements arranged one above and the other below said flange, the lower element being seated on the end of said adapter, a clamping sleeve threaded upon said adapter and having an inturned flange at its outer end engaging the resilient support element, the diameter of said packing cylinder being substantially less than the internal diameters of the casing, the adapter, and of the flange of said clamping sleeve, whereby substantial tilting movement of said cylinder on its said resilient supporting elements is permitted and a packing plunger mounted on said pump rod and reciprocating within said cylinder.

4. In a pump, the combination of a tubular casing, an adapter at the end of said casing, a

pump rod packing cylinder extending into said casing and provided with an annular supporting flange, inner and outer annular resilient supporting elements on opposite sides of said flange, the inner element being seated on the end of said adapter, a clamping sleeve threaded upon said adapter and having an inturned flange at its outer end engaging the resilient support element, the diameter of said packing cylinder being substantially less than the internal diameters of the casing, the adapter, and of the flange of said clamping sleeve, whereby substantial tilting movement of said cylinder on its said resilient supporting elements is permitted, a pump rod provided with a packing plunger reciprocating within said packing cylinder and having a plurality of spaced packing ring grooves, and split resilient metallic packing rings arranged in said packing ring grooves.

5. In a pump, the combination of a tubular casing, an adapter at the end of said casing, a pump rod packing cylinder extending into said casing and provided with an annular supporting flange, inner and outer annular resilient supporting elements on opposite sides of said flange, the inner element being seated on the end of said adapter, a clamping sleeve threaded upon said adapter and having an inturned flange at its outer end engaging the resilient support element, the diameter of said packing cylinder being substantially less than the internal diameters of the casing, the adapter, and of the flange of said clamping sleeve, whereby substantial tilting movement of said cylinder on its said resilient supporting elements is permitted, and a pump rod provided with a packing plunger reciprocating within said packing cylinder.

6. In a pump, the combination of a tubular casing, a pump rod packing cylinder disposed within said casing to extend therefrom and having an annular supporting flange, inner and outer resilient supporting elements disposed on opposite sides of said flange and tiltably supporting said cylinder within the casing, the inner being in supported relation to the cylinder, a threaded clamping sleeve engaging the outer element, a pump rod provided with a packing plunger reciprocating within said packing cylinder and having vertically spaced packing ring grooves therein, and resilient split metallic packing rings arranged in said grooves.

7. In a pump, the combination of a tubular casing, a pump rod, a pump rod packing cylinder disposed within said casing to extend therefrom and having an annular supporting flange, inner and outer resilient supporting elements disposed on opposite sides of said flange, the inner being in supported relation to the cylinder, a threaded clamping sleeve engaging the outer element and a packing plunger mounted on said pump rod and reciprocating within said cylinder.

8. In a pump, the combination of a tubular casing, a pump rod, a pump rod packing cylinder extending into said casing, means for tiltably supporting said packing cylinder within said casing, said supporting means including combined resilient supporting and packing elements for the cylinder, a pump rod packing plunger mounted on said pump rod to reciprocate within said packing cylinder and having vertically spaced packing ring grooves therein, and split resilient packing rings arranged in said packing ring grooves.

CYRUS C. JETTER.
